UNITED STATES PATENT OFFICE.

CYRA B. WATTLES, OF PROVIDENCE, RHODE ISLAND, ASSIGNOR, BY MESNE ASSIGNMENTS, TO ELECTRIC FLOOR SURFACER COMPANY, OF GARDINER, MAINE, A CORPORATION OF MAINE.

FLOOR-DRESSING MACHINE.

No. 881,639.

Specification of Letters Patent. Patented March 10, 1908.

Application filed June 12, 1905. Serial No. 264,853.

To all whom it may concern:

Be it known that I, CYRA B. WATTLES, a citizen of the United States, residing at Providence, in the county of Providence and 5 State of Rhode Island, have invented a new and useful Improvement in Floor-Dressing Machines, of which the following is a specification.

This invention has reference to an improvement in floor dressing machines and more particularly to an improvement in 10 means for adjusting the dressing roll of a floor dressing machine.

In a floor dressing machine supported on 15 three or more wheels it is essential that the dressing roll (covered with an abrasive or polishing material) should be adjustable vertically so as to bring the dressing roll more or less into engagement with a floor. In practice I find that the dressing roll should be adjusted to bear hard on a floor when covered with an abrasive material such as sand paper, and lightly on the floor when covered with a 20 polishing material such as pile fabric.

25 The object of my invention is to improve the construction of a floor dressing machine, whereby the dressing roll is adjustable toward or away from a floor and securely held in the adjusted position in the machine.

30 My invention consists in the peculiar and novel construction of a floor dressing machine comprising a frame, a handle pivotally secured to the rear of the frame, three or more wheels rotatably secured to the frame, 35 a motor secured to the frame, a dressing roll shaft, a dressing roll secured to the shaft, adjustable eccentric bearings in the frame supporting the dressing roll shaft, vertical arms on the eccentric bearings, means for rigidly

40 connecting the vertical arms, upwardly-extending brackets in which are semi-circular slots on the frame, bolts extending through the semi-circular slots and the vertical arms on the eccentric bearings whereby the bearings 45 are rigidly secured in the adjusted position, and means for operatively connecting the motor with the dressing roll shaft, with details of construction, as will be more fully set forth hereinafter.

50 Figure 1 is a side view of my improved floor dressing machine, showing the means for adjusting the dressing roll, and means for operatively connecting the dressing roll adjusting mechanism with the handle, shown 55 in broken lines, and showing a portion of the

handle broken away to more clearly show the invention, and Fig. 2 is an enlarged sectional view taken on line X X of Fig. 1 through the dressing roll adjusting mechanism.

In the drawings, *a* indicates the frame, *b* the handle, *c c* the rear wheels, *d* the forward wheel, *e* the motor, *f* the dressing roll shaft, *g* the dressing roll, *h* the dressing roll adjusting mechanism, and *i* the driving belt of my 60 improved floor dressing machine.

The frame *a* is constructed to have the body portion *a'* adapted to hold the motor *e*, the bifurcated lug *a²* on the rear of the frame, the forwardly-extending arms *a³ a³* on the 70 ends of each of which is formed the hub *a⁴* having the circular opening *a⁵* and the upwardly-extending brackets *a⁶* in which is the semi-circular slot *a⁷*, as shown in Fig. 1.

The handle *b* has a T-shaped upper end *b'* 75 and a lug *b²* on its lower end. An adjusting bolt *b³* is screw-threaded through the lug and bears on the rear of the frame *a*. The lower end of the handle *b* is pivotally secured to the bifurcated lug *a²* by the pin *b⁴*, as shown in 80 Fig. 1.

The wheels *c c* are rotatably secured one on each side of the frame adjacent the rear to the axles *c' c'* which are secured in any well known way to the frame *a*. The forward 85 wheel *d* is secured centrally to the axle *d'* which is rotatably secured at each end in bearings in the arms *a³ a³*, as shown in Fig. 1.

The motor *e* may be of any kind desired. In the preferred form I use an electric motor 90 having the driving shaft *e'* with the pulley *e²* and the casing *e³* secured to the body portion *a'* of the frame *a* by bolts or other means.

The dressing roll *g* is secured to the shaft *f* 95 and is covered with an abrasive material, such as sand paper or with a polishing material such as pile fabric. A pulley *f'* is secured to the power end of the shaft *f*, as shown in Fig. 2.

The dressing roll adjusting mechanism *h* consists of two eccentric bearings *h' h'* each bearing being rotatably supported in the circular opening *a⁸* in a hub *a⁴* on the forwardly-extending arms *a³ a³* of the frame and constructed to have the off-center hole *h²* for the dressing roll shaft *f* and the vertical arm *h³* formed integral with the bearing *h'*, as shown in Fig. 2. The vertical arms *h³ h³* are rigidly connected together by the rod *h⁴* which ex- 105 110

tends through semi-circular slots in the brackets a^6 a^6 and through holes in the arms h^3 h^3 where the ends of the rod are secured by the nuts h^5 h^5 . A bolt h^6 extends through 5 a semi-circular slot a^7 in each of the brackets a^6 a^6 and through a hole in the vertical arms h^3 h^3 where it is secured by a nut h^7 , thus adjustably securing the arms h^3 to the bracket a^6 . A rod h^8 may be pivotally connected to 10 one of the vertical arms h^3 and to the handle b , as shown in Fig. 1, thereby operatively connecting the dressing roll adjusting mechanism h with the handle. By moving the vertical arm h^3 in either direction from the 15 central position, as shown in Fig. 1, the dressing roll g is brought heavily or lightly into contact with a floor.

In the operation of my improved floor dressing machine the dressing roll g is 20 revolved at a high rate of speed on a floor by the motor e through the belt i connecting the pulley e^2 on the motor with the pulley f' on the dressing roll shaft f , while the operator moves the machine on the floor by the handle b . When the connecting rod h^8 is used 25 the dressing roll is adjusted by adjusting the bolt b^3 on the lower end of the handle b , as shown in Fig. 1, and the operation of the dressing roll on the floor may be discontinued 30 at any time without stopping the motor e by raising the handle b .

It is evident that the hole h^2 for the dressing roll shaft f could be placed in any off-center position in the eccentric bearing h' , 35 and an idler pulley could be used for adjusting the tension of the belt i on the pulleys e^2 and f' without materially affecting the spirit of my invention.

Having thus described my invention, I 40 claim as new and desire to secure by Letters Patent:—

1. A floor dressing machine comprising a frame, wheels rotatably secured to the frame, a motor secured to the frame, a dressing roll shaft, a dressing roll secured to the shaft, eccentric bearings supporting the dressing roll shaft and rotatably held in the frame, means

for adjusting the eccentric bearings to raise or lower the dressing roll, and means for operatively connecting the motor with the dressing roll shaft.

2. A floor dressing machine comprising a frame, a handle pivotally secured to the frame, wheels rotatably secured to the frame, a motor secured to the frame, a dressing roll shaft, a dressing roll secured to the shaft, eccentric bearings supporting the dressing roll shaft and rotatably held in the frame, means for rigidly connecting the eccentric bearings together, means for adjustably securing the eccentric bearings to the frame, whereby the dressing roll is adjustable vertically in the frame, and means for operatively connecting the motor with the dressing roll shaft.

3. In a floor dressing machine, the combination of a frame a having the forwardly-extending arms a^3 a^3 on the ends of each of which is formed the hub a^4 having the circular opening a^5 and the upwardly-extending bracket a^9 in which is the semi-circular slot a^7 , a motor e secured to the frame, a dressing roll shaft f , a dressing roll g secured to the shaft f , a dressing roll adjusting mechanism h consisting of the eccentric bearings h' h' each eccentric bearing being rotatably supported 70 in a hub a^4 on the forwardly extending arms a^3 a^3 of the frame and having the off-center hole h^2 for the dressing roll shaft f and the vertical arm h^3 , a roll h^4 rigidly secured to the arms h^3 h^3 by the nuts h^5 h^5 , a bolt h^6 extending through each semi-circular slot a^7 in the brackets a^6 a^6 and through a hole in the arms h^3 h^3 where it is secured by the nut h^7 , whereby the dressing roll g is adjustable vertically and secured in the adjusted position, and 75 means for operatively connecting the motor e with the dressing roll shaft f , as described.

In testimony whereof I have signed my name to this specification in the presence of two subscribing witnesses.

CYRA B. WATTLES.
